UNITED STATES PATENT OFFICE.

HOWARD EARL HOOVER, OF CHICAGO, ILLINOIS, ASSIGNOR TO THE HOOVER SUCTION SWEEPER COMPANY, OF NEW BERLIN, OHIO, A CORPORATION OF OHIO.

DESIGN FOR A BRUSH FOR SUCTION-CLEANERS AND THE LIKE.

52,238.

Specification for Design.

Patented July 30, 1918.

Application filed January 18, 1918. Serial No. 212,403. Term of patent 14 years.

To all whom it may concern:

Be it known that I, HOWARD EARL HOOVER, a citizen of the United States, residing at Chicago, in the county of Cook and State of Illinois, have invented a new, original, and ornamental Design for Brushes for Suction-Cleaners and the like, of which the following is a specification, reference being had to the accompanying drawing, forming part thereof.

Figure 1 is a side elevation of a brush

for suction cleaners and the like showing the design;

Fig. 2 is a cross section thereof.

I claim:—

The ornamental design for a brush for suction cleaners and the like as shown.

HOWARD EARL HOOVER.
